Attorney.

UNITED STATES PATENT OFFICE.

ARSENE B. DES ROCHES, OF PROVIDENCE, RHODE ISLAND, ASSIGNOR TO LIBERTY CARBURETOR COMPANY, A CORPORATION OF DELAWARE.

VAPORIZER.

1,315,475.

Specification of Letters Patent. Patented Sept. 9, 1919.

Application filed April 18, 1919. Serial No. 290,905.

To all whom it may concern:

Be it known that I, ARSENE B. DES ROCHES, a citizen of the United States, residing at Providence, in the county of Providence and State of Rhode Island, have invented certain new and useful Improvements in Vaporizers, of which the following is a specification.

My invention relates to electric vaporizers for the carbureters of internal combustion engines, and relates more particularly to the nozzle thereof.

The essential objects of my invention are to successfully vaporize the less volatile hydrocarbon fuels; to insure a maximum of heat with safety and with a small expenditure of electric current; and to attain these ends in a compact, substantial, and inexpensive structure.

20 To the above ends essentially my invention consists in such parts and such combinations of parts as fall within the scope of the appended claims.

In the accompanying drawings which form a part of this specification,

Figure 1 is a front elevation of a carbureter, and

Figs. 2 and 3, enlarged sections on lines 2—2 and 3—3 respectively of Fig. 1.

30 Like reference characters indicate like parts throughout the views.

In the drawings 5 is the vertical portion and 6 the horizontal portion of the carbureter casing constituting the air conduit. 35 The tank 8 is integral with the wall of the portion 5, and fast in the base of the portion 6 is a nozzle indicated in a general way as 10.

In detail the nozzle has a body 12 terminating at its lower end in a shank portion 13 having an external attaching thread 14. The usual central fuel passage 16 is contracted near the top of the body as at 17 to facilitate the vaporizing discharge through 45 a conical cavity 18. Integral with the body above the shank 13 is a circular base 20 with a vertically disposed peripheral flange 21, embracing a fiber disk 23 with an upwardly directed peripheral flange 24.

50 Through a central opening 25 in the fiber disk extends a mica insulating sleeve 26 resting on the base 20 and embracing the body 12. A brass washer 28 rests on the disk 23 and engages the flange of the latter. A 55 cylindrical brass jacket 30 rests on the disk

28 and is embraced by the flange 24. The jacket embraces a mica insulating lining or tube 31 of equal length. Resting on the top of the sleeve 26 and engaging the sleeve 31 is a brass annular disk 32 provided with a 60 perforation 33. Resting on the top of members 30 and 31 is a fiber disk 37, provided with a depending extension 38 resting on the disk 32. The upper portion of the body has an external thread 41. The portion 38 65 has a circular cavity 43 in its lower face. Upon the member 37 is a brass washer 45; and a nut 46 engages the thread 41. Surrounding the sleeve 26 is a helical resistance coil 48 whose upper end 49 passes through 70 the perforation 33 and terminates in the cavity 43 where it is electrically grounded in the frame through the disk 32 and body 12. The opposite end 50 of the coil engages the disk 28 and passes through a perforation 75 51 in the sleeve 31 and contacts with the jacket 30.

An electrode 53 mounted in the wall 6 of the casing is in contact with the jacket 30 of the nozzle and is connected by a binding 80 screw 55 to a circuit wire 57 extending to any usual convenient source of electrical energy 58. Diagrammatically the electric circuit is shown completed by the wire 60.

In operation the fuel passes from the tank 85 8 into and through the passages 16 and 17 in the usual well known manner. The electric current of the circuit develops heat in the resistance coil 48 sufficient for raising the temperature of the fuel, passing through 90 the nozzle the desired degree. The current passes from the electrode 53 into the jacket 30; thence to the coil end 50, and through the coil and coil end 49, and disk 32 to the body 12, or, as diagrammatically expressed, 95 through the wire 60 to the battery 58.

I claim:

1. In a vaporizer, the combination with the nozzle body, of a base on the body, an insulating disk upon the base, a metallic 100 disk on the insulating disk, an insulating sleeve embracing the body, a metallic jacket resting on the metallic disk, an insulating lining in the jacket, a metallic disk on the body above the insulating sleeve, an insulating washer on the body above the second metallic disk, and a resistance coil between the insulating sleeve and lining in contact with both metallic disks.

2. In a vaporizer, the combination with 110

the nozzle body, of a base on the body, a disk of insulating material on the base, a flange on the disk, a metallic disk on the disk within the flange, a metallic jacket on the metallic disk and embraced by the flange, an insulating lining in the jacket, an insulating sleeve on the body engaging the metallic disk and insulating disk, a metallic washer on the body resting on the sleeve and engaging the lining, an insulating washer on the second metallic disk, and a helical resistance coil between the lining and sleeve engaging both metallic disks.

3. In a vaporizer, the combination of a

nozzle body, provided with external thread, 15 a base on the body, an insulating disk on the base, a metallic disk on the first disk, an insulating sleeve on the body separating the metallic disk from the body, a metallic jacket resting on the metallic disk, an insulating lining in the jacket, an insulating washer on the body and engaging the jacket, a nut on the body engaging the thread, and a resistance coil between the sleeve and lining.

In testimony whereof I have affixed my signature.

ARSENE B. DES ROCHEs.
